UNITED STATES PATENT OFFICE.

JAMES A. MANSON, OF SPRINGFIELD, MASSACHUSETTS.

MACHINE FOR BAGGING CHARCOAL.

993,696.

Specification of Letters Patent. Patented May 30, 1911.

Application filed July 15, 1910. Serial No. 572,159.

To all whom it may concern:

Be it known that I, JAMES A. MANSON, a citizen of the United States of America, residing at Springfield, in the county of 5 Hampden and State of Massachusetts, have invented new and useful Improvements in Machines for Bagging Charcoal, of which the following is a specification.

The present invention relates to improvements in machines for bagging charcoal.

The object of the invention is to provide a mechanism that will effectually and rapidly deliver charcoal into bags of suitable size and at the same time effect the shaking 15 down of the charcoal thoroughly into the bag; and, further, to remove from the charcoal the dust and small pieces which necessarily accompany this material when shipped in bulk.

20 In the drawings forming part of this application,—Figure 1 is a front elevational view of the machine looking toward the discharge or bag-filling end portion. Fig. 2 is a side elevation showing the perforated 25 chute and the dust-collecting receptacle, the main drive-shaft with the links for vibrating the chute, the lever mechanism for elevating and depressing the receptacle platform, and the means for striking the receptacle supporting platform. Fig. 3 is a sectional elevation of the machine showing the end of the chute into which charcoal that is to be screened and packed into the bags is delivered, the section being taken on line 30 3—3 of Fig. 5. Fig. 4 is a longitudinal sectional view of the machine on the line 4—4 of Fig. 5 clearly indicating on an enlarged 35 scale the means for raising and lowering the receptacle platform and the means for imparting a blow to the bottom portion of the platform. Fig. 5 is a plan view clearly indicating the relative positions of the chute-shaking mechanism and the relation of the receptacle platform to the chute. Fig. 6 is 40 an enlarged detail, horizontal view of the receptacle platform on the line 6—6 of Fig. 1. Fig. 7 is an enlarged detailed view of 45 the receptacle and its supporting platform in the receiving or depressed position on the line 7—7, Fig. 1. Fig. 8 is an enlarged sectional detailed view of the receiving receptacle in an elevated or receiving position on the line 8—8 of Fig. 1.

50 Referring to the drawings, α designates the bottom portion of the framework to

which are secured the front and rear uprights b and c . Mounted for rotation in the uprights is a main crank-shaft d that is connected by means of links e and f , to an inclined chute g . The upper portion of the chute is provided with a screen or perforated bottom, shown at h , while the lower portion is made solid, as indicated at i . The links e and f are connected to a brace-piece e' which extends the length of the chute on the underside thereof. This chute is arranged in an inclined position and extends from the rear to the forward portion of the machine. The links e and f , when actuated by the driving-shaft d , will vibrate or oscillate the chute g in a transverse direction, and in order to permit this swinging or oscillatory movement, the chute is hung on the framework by the links j which are pivotally supported on the uprights, as shown at m .

A receiving platform for the material is located at the receiving end of the chute g , as shown at o , and a suitable gate p is pivoted to the upright c and provided with means for varying the degree of inclination of the chute, such means being indicated at q , which consists merely of a cord or other flexible connection. The object of this gate is to deflect the material into the chute when thrown therein by the workmen. The curved lower part of the screen portion h of the chute g is also provided with a vertically movable gate r and with means s for adjusting the same so as to gage the rate of flow of the material downward toward the outlet end.

Located beneath the perforated portion h , and parallel thereto, is an inclined platform t for receiving the dust or small particles that sift through the screen portion h . This material is caught or discharged into a receptacle u located at the lower outlet end of said platform. The material that has been cleaned passes from the screen part h onto the part i which is also vibrated, being secured to the part g , and from there is discharged into the receptacles v which rest upon the platforms x .

Referring to Fig. 1 of the drawings, it will be noticed that one of the receptacle-receiving platforms x is down while the other is elevated. The receiving receptacles v are each located within a semi-circular member z which is shown on an enlarged scale in

Fig. 6 in horizontal section, against which the charcoal-receiving receptacle or bag *v* rests, as clearly shown in Figs. 6, 7, and 8. This semi-circular member is secured to the platform *x*, as indicated at *z*¹ by means of a rivet 2, and these members *z* are secured to a plate or gate 3,—two of which are shown, —one for each receptacle.

4 designates a lever that is pivoted at 5 to a cross-beam 6. This lever is attached to the plates 3 at the points 7 and 8 by means of the links 9 and 10 respectively. The outer end of the lever 4 is connected to a link 11 that extends upward, and its upper end is attached to a hand lever 12 which is pivoted to the upright or a side of the frame, as shown at 13.

When the lever 12 is operated, one of the platforms *x* is elevated, and the other depressed carrying with them the receptacles *v*; at the same time the plates 3 are operated,—one of which is shown in Fig. 1 with its upper portion or end 14 elevated above the bottom curved surface 15 of the outlet 25 portion of the part *z*,—the other plate being depressed as indicated, its upper edge being shown in dotted lines at 17 below the curved surface 15, thus permitting the charcoal to flow freely from the curved edge 15 into 30 the funnel 18 of the receptacle at the left-hand side of the machine, and the part 14, acting as a deflector to turn or cause the downwardly flowing material to fall into one of the funnels 18, while the other funnel is 35 in an elevated position. The funnels 18 are secured to the plates or gates 3 by means of a bracket 19 (see Fig. 7).

When the platform *x* is in the position shown in Fig. 8, the coal-receiving receptacle can be readily removed since the lower portion 20 of the funnel is then elevated above the curved part *z*, and during the filling operations of one of the receptacles the other may be removed and emptied and a 45 new one substituted therefor so that when the first one has been filled and the lever 12 operated, the reverse operations take place; that is the filled one is elevated and the empty one depressed, causing the plates 3 50 to shut off the flow of material to the full one and allow it to discharge into the empty one.

In order to shake the material down into one of the bags that is being filled, the platform *x* is struck a blow from the underside by means of a transverse bar 21, which is shown in Fig. 1, and extends across the width of the machine and under both of the platforms *x*, as shown, its opposite ends 60 being connected thereto, by means of rods 22 which extend upward and are attached to the standards *c*, as shown in Figs. 3 and 4, by means of the plates 23. The upper ends of said rods are pivotally connected 65 with a shaft 24 which is operated from the

main crank shaft *d* by means of the pitman or link 25 that engages a crank-arm 26 on the shaft 24. The shaft 24 carries an arm 27 that is connected to the rods 22. The length of the arm 27 is such that the blows 70 that are imparted to the platform *x* not only strike the platform but actually lift it and carry it upward a short distance so that on the downward movement the charcoal is given a sudden or settling movement 75 when the bars 21 leave the platform. When the bars 21 leave the underside of the platforms *x*, the pins *z*² which are secured to the part *z* will strike the lower end of the wall of the slot *z*³ in the link *z*⁴ which link 80 is attached to the lever 4 by means of the pin 4¹ causing a jarring effect to the bags *v*. The plates or gates 3 are guided and held during their operation by means of the slot and pin constructions shown at *z*¹ and *z*². 85 The pin is secured to the cross-beam 6. A similar construction is shown at the upper end of the plates 3, as indicated at *z*³ and *z*⁴.

It should be observed that the radial 90 distance from the pivotal point 5 of the lever 4 is greater to the links 9 and 10 than from the point 5 to the links or hangers *z*⁴, the point of attachment being shown at 4¹. The object of this arrangement is for the 95 purpose of causing the plates 3 and the funnels 18 to move faster than the platforms *x*, whereby the funnel which is elevated (see Fig. 8) will then be lifted above the part *z* and out of the mouth of the bags *v*, 100 thus permitting the bags to be readily removed from the platforms *x*. Projecting upwardly from the cross-bar *g*¹ are ears *g*² which bear against the arc-shaped piece *g*³ to which the lower end of the chute *g* 105 engages, see Figs. 3 and 4. The upper ends of the gates or plates 3 are guided or run under the depending irons *a*¹ (see Figs. 7 and 8) in order to hold them near the lower end of the chute *g*. 21¹ designates a stiffening iron for the platform *x*. This iron is provided with slots 21² in order to permit the pins *z*² of the part *z* to slide thereon during the adjustment of the platforms *x*, and also to permit the part 21 to slide 110 up and down to impart a jarring effect to the platforms *x*. *x*¹ designates a bar for stiffening the part *z*. 40 designates braces for the member 21 and extends from the upright irons 22 to the striker-bar 21. This 115 operation therefore thoroughly settles or causes the particles of charcoal to fill the entire space of the bags.

28 designates a belt-shipper that is slidably mounted in uprights *b* and *c* by means of the gears 29, and is for the purpose of shifting the belts 30 and 31 onto the tight and loose pulleys 33 and 34 at the opposite ends of the machine. 125

The chute shown herein may, if desired 130

be entirely solid and not reticulated, as the machine is capable of use for bagging various materials.

What I claim, is:—

5. 1. In a charcoal-bagging and cleaning machine, the combination with a vibratory receiving chute, means for vibrating said chute, of a platform for receiving a receptacle to be filled, means operable from the 10 chute for continuously elevating and depressing the platform during the filling operation of the receptacle, and means to cut off the flow of material from the chute to one of the receptacles when the other is being filled.
2. In a charcoal bagging machine, the combination with the frame thereof, of a chute, means for vibrating the chute, a plurality of receptacle-receiving platforms, connecting means between the chute and the platforms for operating the platforms, a gate attached to each platform and movable therewith, said gates being adapted to close the lower end of said chute, means for elevating one platform and depressing the other, whereby the flow of material is shut off from one receptacle and deflected into the other.
3. In a charcoal bagging machine, the combination with the framework thereof, of an inclined chute mechanism, means for vibrating the same, of a plurality of receptacle-receiving platforms, a gate carried thereby and adapted to close the lower end 35 of the chute, a funnel for directing the flow of material into the receptacle from the chute, manually operable means for elevating one of the platforms and depressing the other, and simultaneously lifting the funnels from the mouth of the receptacle, and means connected to the chute for imparting an upward blow to the lower side of said platform, whereby the material is shaken down into the receptacle during the filling 45 operations.

4. In a bagging machine, the combination with the frame thereof, of a vibratory chute, a plurality of platforms for receiving the receptacles, a shaft extending longitudinally 50 of the machine, and a second shaft extending transversely thereof, connecting means

between the two shafts, a transverse bar attached to the second shaft and located beneath the platforms for receiving the receptacles to be filled whereby the platforms 55 may be given a blow from said bar, and manually operable means for elevating one platform and depressing the other so that only one of the platforms is struck at a time.

5. In a bagging machine, the combination with the frame thereof, an inclined chute for delivering the material to the receptacles, a plurality of platforms for receiving the receptacles, a lever pivoted to the frame, a 65 link connection between the platforms and the lever, and means for operating said lever, a gate associated with each platform and adapted to move therewith, the elevated gate extending across the delivery end of the 70 chute, whereby the flow of material is deflected toward the depressed platform.

6. In a bagging machine, the combination with the frame thereof, of a chute for directing the flow of material to be bagged, a 75 platform for receiving the bags to be filled, a gate associated with the platform and having a funnel attached thereto for receiving the material as it flows from the chute and directing it into the bag, and mechanism 80 for imparting a relative movement between the funnel and the platform, whereby when the platform is elevated the lower end of the funnel will be drawn away from the platform, as described.

7. In a bagging machine, the combination with the frame thereof, of an inclined chute, means for vibrating said chute, and gate devices for varying the flow of the material through the chute, a pair of platforms for 90 receiving the receptacles to be filled, a bar located beneath said platforms, and means for simultaneously elevating said bar in unison with the movements of the chute, the travel of the bar being such that a blow is 95 imparted to the lower side of the platform for effecting a jarring or shaking down of the material as it flows into the bags.

JAMES A. MANSON.
